(57) **CLAIM**

The ornamental design for an article hanger, as shown.

DESCRIPTION

FIG. 1 is a front perspective view of an article hanger in accordance with the present invention;

FIG. 2 is a left side view thereof;

FIG. 3 is a right side view thereof;

FIG. 4 is a front side view thereof;

FIG. 5 is a back side view thereof;

FIG. 6 is a top side view thereof; and,

FIG. 7 is a bottom side view thereof.

The broken lines in the drawings depict portions of the article hanger that form no part of the claimed design.
